(57) CLAIM

The ornamental design for a golf head cover, substantially as shown and described.

DESCRIPTION

FIG. 1 is a perspective view of the golf head cover.

FIG. 2 is a side view of the golf head cover, the opposite side being a mirror image.

FIG. 3 is a front view of the golf head cover.

FIG. 4 is a top view of the golf head cover.

FIG. 5 is a bottom view of the golf head cover.

FIG. 6 is a cross sectional view of the golf head cover taken on line 6—6 of FIG. 2; and,

FIG. 7 is a perspective view of the golf head cover.

The broken line showing is for illustrative purposes only and forms no part of the claimed design.
